FIG. 1

FIG. 2

FIG. 3

FIG. 4

FIG. 5

FIG. 6

FIG. 1 is a perspective view of the new design for a truck rack showing the design affixed to a pickup truck shown in broken lines. The truck forms no part of the new design for the truck rack but is illustrated to show its environmental relationship when in use;

FIG. 2 is a top plan view thereof;

FIG. 3 is a side elevational view thereof;

FIG. 4 is a bottom plan view thereof;

FIG. 5 is a front elevational view thereof; and

FIG. 6 is a rear elevational view thereof.

We claim:

The ornamental design for a truck rack, as shown and described.
